UNITED STATES PATENT OFFICE.

FRED C. CAMERON, OF CHICAGO, ILLINOIS, ASSIGNOR TO UNION METAL PRODUCTS COMPANY, OF CHICAGO, ILLINOIS, A CORPORATION OF DELAWARE.

BRACKET FOR CAR-DOORS.

1,191,563.

Specification of Letters Patent. Patented July 18, 1916.

Application filed April 17, 1916. Serial No. 91,599.

To all whom it may concern:

Be it known that I, FRED C. CAMERON, a citizen of the United States, residing at Chicago, in the county of Cook and State of Illinois, have invented new and useful Improvements in Brackets for Car-Doors, of which the following is a full, clear, and exact description.

My invention relates to brackets for supporting the sliding doors of freight cars, and particularly to brackets in which anti-friction rollers are employed.

The object of my invention is to provide a bracket having a convexed anti-friction roller or wheel upon which the door is reciprocably mounted, and to otherwise construct said bracket so that when the door has been moved inward by the engagement of a flange depending from the lower edge thereof with said roller said flange will be held out of engagement with said roller and not interfere with the rotation thereof. This I accomplish by the means hereinafter fully described, and as particularly pointed out in the claims.

In the drawings: Figure 1 is a side view of my invention. Fig. 2 is a front elevation of the same. Fig. 3 is a vertical transverse section taken on dotted line 3—3, Fig. 2.

Referring to the drawings, A represents a supporting-plate which is secured to the side of a car by rivets *a* that extend through one leg of the lower end of a vertically disposed angle-iron post *b* and through the web of a channel-beam side-sill *B* below the horizontal plane of the decking *C* of the car. The decking *C* is suitably supported upon the upper flange of channel-beam *B*, and at the door-way of the car the ends of this decking project beyond the vertical plane of said channel-beam to form the sill of the door, the sides of which latter are formed by the outwardly projecting legs of the post *b*, whose outer edges are, preferably, flush with the outer edge of the door-sill.

Two corresponding arms *D*, *D*, project outwardly and, preferably, upward at a suitable angle from said plate *A* and have their ends connected by a suitable transverse vertically disposed front-plate *E*, the upper edge of which projects upward above arms *D*, *D*, a suitable distance. This front-plate *E* is parallel to the side of the car, and midway between arms *D*, *D*, it is provided with a tubular boss *J*, the axis of which is at

right angles to plate *A* and the bore of which is, preferably, square in cross-section and projects to the rear of plate *E* a distance greater than it projects to the front of said plate. The portion thereof extending to the rear is cylindrical and has a roller *F* journaled thereon. This roller may be made dished, as shown in Fig. 3 of the drawings, or it may be made solid and with the side thereof next the car convexed. The roller is retained in position by means of a bolt *G*, the barrel of which is made square to fit into the square bore of boss *J*, and it is secured in said boss by a suitable rivet or pin *H* that is passed through suitable apertures in the outwardly projecting portion of boss *J*. The rear end of bolt *G* is provided with a head *g* whose diameter is greater than that of said boss, and this head is seated in the countersunk edges *f* of the inner end of the central opening of roller *F*.

A sliding door *I* of any suitable construction is employed to close the door-way of the car, and the lower edge of this door is provided with a metallic tread *K* consisting, preferably, of a Z-bar having comparatively long flanges. The web of this Z-bar tread is attached directly to the lower edge of the door in any suitable manner and has its outer flange *e* projecting upward andlapping against the lower margins of said door, and its inner flange *k* projecting downward in a vertical plane parallel to but slightly in front of that of the inner surface of the door. This door *I* is supported by suitable brackets so as to slide back and forth in front of the door-way and so that its lower edge will pass in front of the outer ends of decking *C* forming the door-sill, and when said door is moved toward its closed position the end of the tread will fit upon the roller, and at the same time flange *k* thereof will come in contact with the convexed rear side of roller *F*, and it and door *I* will be pushed rearward toward the adjacent side of the car so as to tightly close the door-way, and when said flange *k* reaches the central portion of roller *F* it will engage the convexed side of head *g* of bolt *G* and be held out of engagement with roller *F* and not interfere with its free rotation.

In order to limit the inward movement of flange *k* and door *I*, the upper edges of arms *D*, *D*, are provided with upwardly projecting lugs *L*, but while I prefer to use these

5 lugs they may be dispensed with. The upper edges of arms D, D, are, preferably, flanged outward, and the rear sides of lugs L may be provided with fins to strengthen them, and between the base of lugs L (which is below the lower edge of flange k of the Z-bar tread K), and the outer ends of said arms, the latter may have upwardly projecting integral wings to which the end edges of front-plate E may be connected in such manner as 10 to reinforce said front-plate.

What I claim as new is:

1. In a car, the combination with a door 15 having a longitudinal flange depending from its lower edge, of a bracket comprising a supporting-plate, an arm projecting therefrom, a front-plate supported by and projecting above the same, and a roller that supports said door having its side nearest 20 the adjacent side of the car convex and adapted to be engaged by said flange, and means for journaling said roller that projects rearwardly from said wall and is provided with a head that retains said roller in position and has its rear end convexed and is engaged by said flange as the latter passes the axis of said roller.

2. In a car, the combination with a door 30 having a longitudinal flange depending from its lower edge, of a bracket comprising a supporting-plate, an arm projecting outward therefrom, a front-plate supported by and projecting above the same, a tubular boss made integral therewith and having its 35 axis at right angles thereto, a roller journaled upon said boss upon which said door travels which has its side nearest the car convexed and adapted to be engaged by said flange, and a bolt seated in the bore of said 40 boss that has a head on its inner end the crown of which is convexed and which retains said roller on said boss and is engaged by said flange as the latter passes the axis of said roller.

45 3. In a car, the combination with a door having a longitudinal flange depending from its lower edge, of a bracket comprising a supporting-plate, an arm projecting outward therefrom, a front-plate supported by and projecting above the same, a tubular 50 boss made integral therewith and having its axis at right angles thereto, a roller journaled upon said boss upon which said door travels which has its side nearest the car 55 convexed and adapted to be engaged by said flange, and a bolt seated in the bore of said boss that has a head on its inner end the crown of which is convexed and which is seated in the rabbeted edge of the inner

60 side of the central opening of said roller with its convexed crown flush with the convexity of the same and is engaged by said flange as the latter passes the axis of said roller.

65 4. In a car, the combination with a door

having a longitudinal flange depending from its lower edge, of a bracket comprising a supporting-plate, an arm projecting therefrom, a front-plate supported by and projecting above the same, a lug projecting 70 upward from said arm between said front-plate and supporting-plate, and a roller having its side nearest the adjacent side of the car convex, and means for journaling said roller that projects rearwardly from said 75 wall and is provided with a head that retains said roller in position and has its rear end convexed and is engaged by said flange as the latter passes the axis of said roller.

80 5. In a car, the combination with a door, a longitudinal Z-bar tread secured to the lower edge thereof and having a flange depending therefrom, of a bracket comprising a suitable supporting-plate, parallel arms 85 projecting outward therefrom, a front-plate connecting the outer ends of said arms and having an integral boss the horizontal axis of which is at right angles thereto, a roller journaled on the inner portion of said boss 90 and having its inner side convexed and the inner edge of its central opening rabbeted, and a bolt seated in the bore of said boss and having a head whose crown is convexed and is adapted to be seated in said 95 rabbeted head with its crown flush with the convexity of said roller and is engaged by said flange as the latter passes the axis of said roller.

100 6. In a car, the combination with a door, a longitudinal Z-bar tread secured to the lower edge thereof and having a flange depending therefrom, a bracket comprising a suitable supporting-plate, parallel arms projecting outward therefrom having lugs projecting upward therefrom mediate their ends, a front-plate connecting the outer ends of said arms and having an integral boss the horizontal axis of which is at right angles 105 thereto, a roller journaled on the inner portion of said boss and having its inner side convexed and the inner edge of its central opening rabbeted, and a bolt seated in the bore of said boss and having a head whose crown is convexed and is adapted to be seated in said 110 rabbeted head with its crown flush with the convexity of said roller and is engaged by said flange as the latter passes the axis of said roller.

115 7. In a car, the combination with a door having a longitudinal flange depending from its lower edge, of a bracket comprising a supporting-plate, an arm projecting therefrom, a front-plate supported by and projecting above the same, a roller that supports said door and has its side nearest the adjacent side of the car convexed and adapted to be engaged by said flange, and means around which said roller revolves that projects rearwardly from said 120 front-plate 125

slightly beyond said roller whose rear end is adapted to be engaged by said flange as the latter passes the axis of said roller.

8. In a car, the combination with a door having a longitudinal flange depending from its lower edge, of a bracket comprising a supporting-plate, an arm projecting therefrom, a front-plate supported by and projecting above the same, a roller that supports said door and has its side nearest the adjacent side of the car convexed and adapt-

ed to be engaged by said flange and supported by said bracket which when said flange reaches the central portion of the convexed side of said roller holds said flange out 15 of engagement therewith.

In witness whereof I have hereunto set my hand this 5th day of April, 1916.

FRED C. CAMERON.
